UNITED STATES PATENT OFFICE.

ELBERT E. WOOD, OF BROOKLYN, NEW YORK.

IRONING-BOARD.

SPECIFICATION forming part of Letters Patent No. 447,745, dated March 3, 1891.

Application filed June 25, 1890. Serial No. 356,672. (No model.)

To all whom it may concern:

Be it known that I, ELBERT E. WOOD, a citizen of the United States, and a resident of Brooklyn, in the county of Kings and State 5 of New York, have invented new and useful Improvements in Ironing-Boards, of which the following is a specification.

My invention relates to ironing-boards, such as have a clamp at one end to be temporarily 10 attached to the edge of a table and a leg to support the other end; and it consists in an improved contrivance for the connection of said leg with the board which improves the usefulness of the board for some purposes, 15 all as hereinafter fully described, reference being made to the accompanying drawings, in which—

Figure 1 is a plan view of my improved ironing-board inverted with the leg folded 20 up and showing a part of the table. Figs. 2 and 3 are longitudinal sections on line xx of Fig. 1, showing the leg of the board in different positions. Fig. 4 is a transverse section of the board on line yy , Fig. 3; and Fig. 5 is 25 an end view of the board with the leg detached.

The board a is made in the usual form of such ironing-boards and has a clamp for fastening one end to a table b , consisting of the 30 cleat c , jaw d , screw e , and lever-nut f , all substantially the same as commonly arranged.

My invention consists in connecting the leg g to the flat metal plate h , instead of directly to the board, and securing said plate 35 to the board a by the angle-cleats i , forming a slideway in the lengthwise direction of the board along which the plate may be shifted to set the leg in different positions and so that the plate may be taken out and be reversed 40 lengthwise, as a further means of shifting the position of the leg, said leg being connected to the plate near one of its ends. The angle-cleats are adjusted so that they press the plate against the surface of the board 45 with sufficient force to hold the plate by fric-

tion against shifting its position when set, but so that the plate may be forced along the cleats by hand without difficulty. This is accomplished by using thin elastic metal for the angle-cleats and adapting them so that 50 when in the normal position, with the plate h removed, the outer flanges assume positions a little nearer to the surface of the board than the thickness of the plate h , as shown in Fig. 5, whereby they grip the plate when it is 55 forced in between them, and press it against the surface of the board and thus hold it by friction, as stated. The cleats i extend the greater part of the length of the board from its middle to the end opposite to the one attached to the table, and thus enable the leg to be set anywhere along the cleats, the plate h being reversed, according as the leg is to be set near the respective ends of the cleats. This enables a long skirt to be placed on the 60 board so as to be ironed the whole length when required.

The leg is hinged to the plate h at j , same as it is usually hinged to the board, to enable it to be folded up and fastened by the hook 70 l when out of use.

I claim—

The combination, with the ironing-board having the clamp for attaching one end to the table, of the leg for supporting the other 75 end, connected to the under side of the board by the adjusting-plate, and the spring-cleats, said cleats forming a slideway for the plate, and said plate being detachable and reversible in said slideway, substantially as described.

In testimony that I claim the foregoing as my invention I have signed my name, in presence of two witnesses, this 30th day of April, 1890.

ELBERT E. WOOD.
